UNITED STATES PATENT OFFICE.

WILLIAM S. WELLS, OF SOUTH BETHLEHEM, PENNSYLVANIA, ASSIGNOR TO BENJAMIN EASTWOOD COMPANY, OF PATERSON, NEW JERSEY, A CORPORATION OF NEW JERSEY.

PROTECTOR MECHANISM FOR LOOMS.

Application filed November 11, 1922. Serial No. 600,264.

This invention relates to means for stopping a loom in case a shuttle fails to be properly boxed. The ordinary means used for this purpose is a feeler device which is normally urged to a position to engage a stopping instrumentality when the batten beats up in case the shuttle fails to be properly boxed in one or the other box, being otherwise held out of that position by the shuttle. But this feeler device imposes normally an impediment to the shuttle impelling force, and it also causes undue wear of the shuttle and other parts, because there is no medium other than the shuttle to assume the pressure of said device at the moment the shuttle is impelled from one box and enters the other. My present invention therefore has for its object to provide means which at the moment the shuttle is impelled from one box and enters the other will be assuming the pressure of said device, thus leaving the shuttle free at this time, said means being made thereupon to release said device so that it can "feel" for the shuttle and if the latter fails to be properly boxed may assume the position for stopping the loom. In carrying out my invention in its best form said means is a detent in the form of spring-pressed lever which normally assumes the pressure of said device, so that the shuttle in either box would be free, and after each flight of the shuttle and before the batten completes its forward stroke is moved to temporarily release said device to enable it to "feel" for the shuttle and stop the loom if the shuttle is not properly boxed.

In the drawings:

Fig. 1 is a front-to-rear sectional view of the batten and breast beam of a loom equipped with the improved stopping mechanism;

Fig. 2 is a sectional view on the line 2—2 of Fig. 1;

Fig. 3 is a sectional view on a smaller scale, taken just forward of the batten;

Fig. 4 is a plan view of the right hand shuttle box in Fig. 3;

Fig. 5 is a fragmentary view, partly in section and on a larger scale, of said shuttle box; and

Fig. 6 is a sectional view on the line 6—6, Fig. 5.

In the drawings *a* is the frame of a loom, *b* its breast beam and *c* the usual structure,

including a batten *d*, arranged to oscillate toward and from the breast beam, *e* being the pitman by which said structure is reciprocated from the crank shaft of the loom.

d' is the back wall of each shuttle box and *f* is its front wall, the bottom of the shuttle box having the usual slot *g* for the picker stick *h* and *i* being the picker arranged on the picker stick so as to travel in the box in the usual way. The front wall of each box is shod on the inside with leather *f'*, the inner end of the wall being beveled away at the inside as shown in Fig. 4 so that the entrance to the box is flaring. The wall *f* has an elongated exterior recess *f*² therein which at *f*³ forms an opening into the interior of the box, and in the recess is arranged a lever *j* fulcrumed to move on a pivot *k* in a horizontal plane and being normally urged outwardly by a spring *l* until the inner end of a slot *m* in the lever engages a pin *n* (Fig. 5). The lever *j* has a rounded tongue *j'* projecting into the opening *f*³ and adapted to protrude therethrough into the shuttle box upon pressing inwardly on said lever.

o designates the shuttle.

In the batten structure *c* under the batten *d* is journaled in the usual way the protector shaft *p*. This shaft carries two upstanding arms *q*, one at each end, they being respectively adapted to bear against the inner or free ends of the lever *j*, and the shaft is normally turned in the direction to hold the arms pressed against the levers by a spiral spring *r* coiled about the shaft and secured at one end to the structure *c* and at the other end to a collar *s* secured on said shaft. The protector shaft carries two daggers *t*, each in the present case arranged on the shaft in a housing *c'* formed therefor in the batten-including structure *c*.

The controller of the loom is here represented as a rock shaft *u* carrying a handle *v* and journaled in the frame *a* under the breast beam. In the loom frame under the breast beam is secured a bracket *w* for a bunter mechanism of well-known construction, the essential elements of which are a lever *x* to be engaged in its notch *x'* by one of the daggers *t* and adapted when so engaged to act against a set screw *y* on the controller *v* to shift the latter to stop the loom, and a buffer slide *z* suitably coupled with the

lever and backed by a rubber cushion 2. There is one of these bunter mechanisms for each dagger.

Forming a part of what I term the "feeler device", which also includes parts *p*, *q* and *t*, and secured on the shaft *p* is a bent arm 3 which extends rearwardly and then upwardly and at its free end has a hardened plate 3' secured thereto so that it projects forwardly and forms in effect a hook. When the batten is nearly at its forward limit this arm is adapted to bear upon a roller 4 secured to the frame. On the pivot 5 between the structure *e* and one of the pitman *e* is arranged to oscillate a bell crank lever 6, which constitutes what I term the detent. This lever has one arm 6^a depending toward the arm 3 and provided at its free end with an angular hardened plate 6^b which coacts 20 hook-fashion with the hook 3' of arm 3. The other arm 6^c of the lever 6 has a set screw 7 against which the pitman *e* may abut. A spring 8 coiled in the bearing portion 6^d of the lever normally tends to turn it 25 in the clockwise direction, being secured at one end to a collar 9 fixed on the stud or pivot 5 and at the other end to the lever.

Operations—The feeler device normally tends to exert pressure on the lever *j* of each 30 shuttle box and so on the shuttle if present in either box. But this tendency, excepting for a short arc when the batten is about half way of its forward movement and which the pitman *e* enters after the shuttle is impelled 35 from one box to the other, is constantly resisted by the detent whose hook 6^b opposes movement of said feeler device in the direction of the arrow in Fig. 1 because said hook then dogs the hook 3'. During movement of 40 the pitman through said arc it is impinging against the set screw 7 and so shifts the detent against the tension of its spring 8 so that the feeler device is tripped. If the shuttle is properly boxed in either box there 45 will then be no movement of the feeler device sufficient to raise the dagger into position to encounter the bunter mechanism, although there will be a slight yielding as to the elastic extremities *q'* of arms *q* and the 50 yielding of the springs 7, which usually will bring the hook 3' too low to be again dogged by the hook 6^b when the detent returns so that the feeler device will again be so dogged only on being shifted backward to permit 55 its becoming again cocked or held by the detent. If the shuttle is improperly boxed movement of the feeler device sufficient to raise the dagger into position to encounter 60 the bunter mechanism will ensue and as the batten proceeds forward the loom will be stopped. Before the forward movement of the batten is completed in any case, the feeler device after performing its feeling or 65 detecting movement will encounter the roller 4 and be shifted back, contrary to the pres-

sure of its spring *r*, until it can be caught and again held by the detent, which by this time the pitman has again cleared. Thus in each cycle or back and forth movement of the batten the feeler device is held retracted for a more or less extent of the cycle so that the impelling of the shuttle and its entry into a box are free of such device, and during the remainder of the cycle the said device is released for detecting or feeling and, if required, for stopping the loom, and thereupon returned and held in its retracted state.

Otherwise stated, instead of the feeler device (which, although its ultimate function is to stop the loom in the present example, is broadly speaking a detector) being constantly urged toward the detecting position to the end that it would actually assume and remain in that position throughout each cycle of the batten if the shuttle were absent in either box, said device or detector is made subject to the control of means which urges it first toward and then from detecting position on each back-and-forth movement or cycle of the batten, such means being here afforded by spring *r* and the roller 4; in the present example, moreover, said spring normally urges the detector into said position and when it is urged therefrom by the means 4 it is further locked in the new position and there retained until, at a later point in the same cycle or back-and-forth movement of the batten, the locking means (detent 6) is caused by the pitman to release the detector.

Hook 6^b has a depending lip as shown in Fig. 1 to prevent this hook in any event overriding hook 3' and so preventing return of the feeler device under influence of roller 4.

The rotation of the crank shaft of the loom illustrated is counter-clockwise.

Having thus fully described my invention, what I claim as new and desire to secure by Letters Patent is:—

1. The combination, with the fixed structure of a loom, a batten movable therein and having a shuttle box, and a shuttle movable on the batten into and out of the box, of a detector movable on the batten into and out of and normally urged into position to detect presence or absence of a shuttle in the box, means to retract the detector from said position at one point in each back-and-forth movement of the batten, means to lock said detector in the retracted position and means at a later point in each such back-and-forth movement to cause release of the detector from the last-named means.

2. The combination, with the fixed structure of a loom, a batten movable therein and having a shuttle box, and a shuttle movable on the batten into and out of the box, of a detector movable on the batten into and out of and normally urged into position

- to detect presence or absence of a shuttle in the box, means on said fixed structure to retract the detector from said position at one point in each back-and-forth movement of the batten, means to lock said detector in the retracted position and means at a later point in each such back-and-forth movement to cause release of the detector from the last-named means.
- 10 3. The combination, with the fixed structure of a loom, a batten movable therein and having a shuttle box, and a shuttle movable on the batten into and out of the box, of a detector movable on the batten into and out of and normally urged into position to detect presence or absence of a shuttle in the box, means to retract the detector from said position at one point in each back-and-forth movement of the batten, means to lock said detector in the retracted position and 20 means to move the batten back and forth and at a later point in each such back-and-forth movement cause release of the detector from the last-named means.
- In testimony whereof I affix my signature.

WILLIAM S. WELLS.
